UNITED STATES PATENT OFFICE.

PERCY I. ANSORGE, OF BROOKLYN, NEW YORK.

DESIGN FOR A LIGHTING-FIXTURE PART.

57,423.

Specification for Design.

Patented Mar. 29, 1921.

Application filed July 12, 1920. Serial No. 395,757. Term of patent 7 years.

To all whom it may concern:

Be it known that I, PERCY I. ANSORGE, a citizen of the United States, residing at Brooklyn, in the county of Kings and State of New York, have invented a new, original, and ornamental Design for a Lighting-Fixture Part, of which the following is a specification, reference being had to the accompanying drawing, forming part thereof.

Figure 1 is a side view of my new design.
Fig. 2 is a plan view of my new design

of a wall plate for electric lights, comprising an ornamental plate, wide at the top and tapering to a point on the bottom, having handles or side extensions above the center, to which arms or supports for holding electric lights may be attached.

I claim:

The ornamental design for a lighting fixture part as shown and described.

PERCY I. ANSORGE.
